UNITED STATES PATENT OFFICE

RAY D. KELL, OF SCOTIA, NEW YORK, ASSIGNOR TO GENERAL ELECTRIC COMPANY,
A CORPORATION OF NEW YORK

TRANSMISSION OF PICTURES OR VIEWS

Application filed September 30, 1929. Serial No. 396,030.

My invention relates to the transmission of pictures or views and has for its principal object the provision of an improved picture receiving apparatus of the cathode ray type which may be utilized to receive pictures transmitted by a transmitting apparatus including a rotatable perforated scanning disc or the like.

In the past, different types of picture receiving apparatus, including a cathode ray device have been utilized. In the utilization of such devices a stream of electrons is projected from one end of a vacuum tube on to a fluorescent screen at the other end where it produces a bright spot, the intensity of the cathode ray being modulated in accordance with the shade of the successive elemental areas of the picture to be produced and the movement of the ray being controlled by an electrostatic or an electromagnetic field which causes it to scan or sweep over the receiving screen. The movement of the cathode ray or the scanning of the receiving screen is usually effected by means of magnetic or electrostatic fields of different frequencies applied to the ray in different directions by means of suitable electrodes. For this purpose two oscillators operating at different frequencies are sometimes employed. This method of scanning, however, is not suitable for use in picture receiving apparatus which is utilized in connection with transmitting apparatus including a rotatable scanning disc or the like, for the reason that it is impossible to establish the proper relation between the rotational speed of the disc and the frequency of the oscillators. In accordance with my invention this difficulty is obviated by the provision of an improved cathode ray picture receiving apparatus which may be readily synchronized with the rotatable disc or other movable part of the picture transmitting apparatus.

My invention will be better understood from the following description when con-

sidered in connection with the accompanying drawing and its scope will be pointed out in the appended claims.

The drawing illustrates a picture receiving apparatus wherein my invention has been embodied.

This apparatus includes a radio receiver 10 through which electrical impulses modulated in accordance with the shade of the successive elemental areas of the transmitted picture are applied to the input circuit of a space discharge device 11. The output circuit of this device includes a source of current shown as a battery 12 the cathode 13 and the anode 14 of a vacuum tube 15. Between the cathode and anode of the vacuum tube 15 is interposed a perforated shield 16. This tube is provided at its left hand end with a fluorescent screen 15'. A stream of electrons from the cathode 13 is projected upon the screen through the shield 16 and the anode 14 and is caused to move through a predetermined cycle of movements by a pair of electrodes 17 and 18 and a pair of electrodes 19 and 20.

It will be noted that the electrodes 18 and 19 are connected to the anode 14 and to the cathode of the discharge device 11. The electrode 17 is arranged to be connected to the cathode 13 through the battery 12, a battery 22 and a space discharge device 21. The electrode 20 is arranged to be connected to the cathode 13 through the battery 12, a space discharge device 23 and the battery 22. A condenser 24 is connected in parallel with the device 21 and a condenser 26 is connected in parallel with the device 23. Variation in the potential applied between the two pairs of electrodes 17 and 18 and 19 and 20 is effected by means of a contact device arranged to be driven by a motor 27. This contact device includes a slip ring 28 connected to the battery 22, a commutator 29 arranged to successively complete a circuit which includes the condenser 26 and a source

of current 31, and a commutator 32 arranged to complete a circuit which includes the condenser 24, and a source of current 34. The apparatus is grounded at a point 35 between the batteries 12 and 22.

5 The operation of the apparatus will be readily understood if it be assumed that no potential is applied between the pairs of electrodes 17 and 18 and 19 and 20. Under these 10 conditions there is applied between the cathode and anode of the cathode ray tube 15 a potential which is modulated in a well known manner in accordance with the shade of the successive elemental areas of the transmitted picture. Due to this potential, a stationary 15 cathode ray is projected on the screen 15', this ray producing a spot of light which is stationary and changes its brilliancy in accordance with potential applied between the cathode 13 and the anode 14. Movement of the 20 cathode ray to scan the screen 15' and produce a picture thereon is effected by means including the contact or commutator device which is driven by the motor 27.

25 The commutator 29 is provided with a plurality of insulation segments interposed between the conductor segments. As this commutator is rotated the condenser 26 is successively charged and discharged, this condenser 30 being charged substantially instantaneously by the battery 31 when the brush of the commutator 29 is in contact with a conductive segment, and being discharged at a substantially constant rate through the device 23 35 when the brush of the commutator is in contact with an insulation segment. Due to the charging and discharging of the condenser 26, a variable potential is applied between the electrodes 19 and 20 and the cathode ray is 40 moved back and forth in one direction for example, horizontally, across the screen 15'.

In order to scan the screen 15', it is of course 45 essential that the cathode ray be moved also in a vertical direction. This result is produced by means of the commutator 32 which is provided with a single insulation segment and a single conductive segment. When the brush of the commutator 32 is in contact with the conductive segment, the condenser 24 is 50 charged substantially instantaneously by the battery 34 and when the brush of this commutator is on the insulation segment the battery 24 is discharged at a substantially constant rate through the device 21. Due to the 55 charging and discharging of the condenser 24, a variable potential is applied between the electrodes 17 and 18 and the cathode ray is moved across the screen 15' in a vertical direction. As a result of this movement the 60 ray successively sweeps over the area of the screen 15'.

The use of a contact or a commutator device for controlling the movement of the ray has the important advantage that the scanning of the screen 15' by the ray may be read-

ily synchronized with the movement of the scanning beam produced by the well known Nipkow disc or apparatus of like character. The apparatus utilized for controlling the movement of the cathode ray is comparatively inexpensive and is much simpler than that heretofore utilized for this purpose.

70 What I claim as new and desire to secure by Letters Patent of the United States, is:

75 1. A picture receiving apparatus including a vacuum tube provided with a screen, with means including a cathode and anode for directing a stream of electrons on to said screen, and with pairs of electrodes for controlling the direction in which said stream is applied to said screen, a plurality of condensers connected respectively to control the potential differences of the pairs of electrodes, means for discharging said condensers at predetermined rates, means for charging the condensers comprising a source of current and a plurality of contact devices in circuit therewith arranged to operate at different frequencies having a fixed relation with one another, and a common driving 80 means for said contact devices.

85 2. A picture receiving apparatus including a vacuum tube provided with a screen, with means including a cathode and anode for directing a stream of electrons on to said screen and with pairs of electrodes for controlling the direction in which said stream is applied to said screen, a plurality of condensers each connected to one of the pairs of electrodes, a plurality of space discharge devices 90 arranged to discharge the respective condensers at different predetermined rates, condenser charging means comprising a source of current and a plurality of contact devices arranged to operate at different frequencies 95 having a fixed relation with each other and a common driving motor for said devices.

100 In witness whereof, I have hereunto set my hand this 27th day of September, 1929.

RAY D. KELL.
